US0D1081473S

(12) **United States Design Patent** (10) **Patent No.:** **US D1,081,473 S**
(45) **Date of Patent:** **** Jul. 1, 2025**

(54) **ELECTRIC BICYCLE**

(71) Applicant: **VEORIDE INC.**, Chicago, IL (US)

(72) Inventor: **Yanke Tan**, Chicago, IL (US)

(73) Assignee: **VEORIDE INC.**, Chicago, IL (US)

(**) Term: **15 Years**

(21) Appl. No.: **29/917,526**

(22) Filed: **Nov. 20, 2023**

(30) **Foreign Application Priority Data**

Oct. 8, 2023 (CN) 202330648215.4

(51) **LOC (15) Cl.** **12-11**

(52) **U.S. Cl.**

USPC **D12/111**

(57) **CLAIM**

The ornamental design for an electric bicycle, as shown and described.

DESCRIPTION

FIG. 1 is a perspective view of an electric bicycle embodying my new design;

FIG. 2 is a perspective view thereof from another angle;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
